UNITED STATES PATENT OFFICE

ARLINE A. GRATZ, OF MINNEAPOLIS, MINNESOTA, ASSIGNOR TO DOMINION ELECTRICAL MANUFACTURING CO., OF MINNEAPOLIS, MINNESOTA, A CORPORATION OF MINNESOTA

DESIGN FOR AN ELECTRICAL GRILL OR SIMILAR ARTICLE

Application filed November 19, 1930. Serial No. 37,723. Term of patent 7 years.

To all whom it may concern:

Be it known that I, ARLINE A. GRATZ, a citizen of the United States, residing at Minneapolis, in the county of Hennepin and State of Minnesota, have invented a new, original, and ornamental Design for Electrical Grill or Similar Article, of which the following is a specification, reference being had to the accompanying drawing, forming part thereof, wherein:

Fig. 1 is a perspective view of an electrical grill or similar article embodying my new design; and

Fig. 2 is a plan view of the same.

What I claim is:

The ornamental design for an electrical grill or similar article, substantially as shown.

ARLINE A. GRATZ.
